UNITED STATES PATENT OFFICE.

SIGMUND HOCHSTADTER, OF NEW YORK, N. Y.

DESIGN FOR A BOTTLE.

40,426.

Specification for Design.

Patented Jan. 4, 1910.

Application filed August 22, 1908. Serial No. 449,881. Term of patent 14 years.

To all whom it may concern:

Be it known that I, SIGMUND HOCHSTADTER, a citizen of the United States, residing in the city of New York, borough of Manhattan, in the county and State of New York, have invented a new, original, and ornamental Design for a Bottle, of which the following is a specification, reference being had to the accompanying drawings, forming part thereof, and in which—

Figure 1 is a side view showing a bottle incorporating my said design, and Fig. 2 is a top view thereof.

In said drawings the bottle is shown comprising essentially a slightly tapering body provided with a series of slightly curved faces at its base having their upper ends rounded and surmounted by a bead, and a

substantially circular bead arranged upon the side of said body having its separated ends merging with the bead surmounting the curved faces along the base of said bottle. The upper portion of said tapering body is rounded and meets a flattened shoulder from the inner rounded portion of which extends a neck having a series of depressed longitudinal faces or panels therein, terminating at their upper ends in a bead arranged just below the mouth of the bottle.

I claim—

The ornamental design for a bottle as shown and described.

SIGMUND HOCHSTADTER.
